(57) **ABSTRACT**

A new *Lantana* plant named 'LANZ0021' having large sized deep cherry pink mature flowers, excellent flower production, moderate plant size and uniform dense mounded habit with medium green foliage.

1 Drawing Sheet

1

Latin name of the genus and species of the plant claimed:
Lantana camara L.

Varietal denomination: 'LANZ0021'.

BACKGROUND OF THE NEW PLANT

The present invention comprises a new *Lantana*, botanically known as *Lantana camara* L., and hereinafter referred to by the variety name 'LANZ0021'.

'LANZ0021' is a product of a planned breeding program. The new cultivar 'LANZ0021' has large sized deep cherry pink mature flowers, excellent flower production, moderate plant size and uniform dense mounded habit with medium green foliage.

'LANZ0021' originates from the cross-pollination between proprietary breeding lines '749-2' and '449-1' made in a greenhouse in July 2015 in Gilroy, Calif., USA. The female parent '749-2', U.S. Plant Pat. No. 28,174, 'LANZ0007', has light orange flower color and a smaller mounding plant habit than 'LANZ0021'. The male parent '449-1', U.S. Plant Pat. No. 23,316, 'LANZ0003', has pale yellow flower color and a smaller mounding plant habit than 'LANZ0021'.

The seed was sown in January 2015 in a greenhouse in Gilroy, Calif. and 'LANZ0021' was selected as one flowering plant within the progeny of the stated cross in March 2015.

The first act of asexual reproduction of 'LANZ0021' was accomplished when vegetative cuttings were propagated from the initial selection in June 2015 in a greenhouse in Gilroy, Calif.

BRIEF SUMMARY OF INVENTION

Horticultural examination of plants grown from cuttings of the plant initiated in September 2015 in Gilroy, Calif., and continuing thereafter, has demonstrated that the combination of characteristics as herein disclosed for 'LANZ0021' are firmly fixed and are retained through successive generations of asexual reproduction.

2

'LANZ0021' has not been observed under all possible environmental conditions. The phenotype may vary significantly with variations in environment such as temperature, light intensity, and day length.

A Plant Breeder's Right for this cultivar has not yet been applied for. 'LANZ0021' has not been made publicly available prior to the effective filing date of this application, notwithstanding any disclosure that may have been made less than one year prior to the effective filing date of this application by the inventor or another who obtained 'LANZ0021' directly from the inventor.

The following traits have been repeatedly observed and are determined to be basic characteristics of the new variety. The combination of these characteristics distinguishes this *Lantana* as a new and distinct variety.

BRIEF DESCRIPTION OF THE PHOTOGRAPHS

The accompanying photographic drawings show typical flower and foliage characteristics of 'LANZ0021' with colors being as true as possible with an illustration of this type. The photographic drawings show in FIG. 1 a close view of an inflorescence, and in FIG. 2 a whole flowering plant.

DETAILED BOTANICAL DESCRIPTION

The plant descriptions and measurements were taken in Gilroy, Calif. in October 2018. The plants were approximately 6 months old and were growing in 14" pots outdoors.

The aforementioned photographs show those same plants as used for the description were taken in Gilroy, Calif. in September 2018 and show 6 month old plants from an outdoor trial.

Color references are made to The Royal Horticultural Society Colour Chart (R.H.S.) 2001.

TABLE 1

DIFFERENCES BETWEEN THE NEW VARIETY
'LANZ0021' AND A MOST SIMILAR VARIETY

	'LANZ0021'	'Bante Cheriasun' (U.S. Plant Pat. No. 19,264)
Flower color:	Cherry Pink	Cherry Pink
Foliage size:	Larger	Smaller
Plant size:	Larger	Smaller

Plant:

Form, growth and habit.—Semi-woody, grown as an annual or perennial; large and dense mounding habit; very well branched.

Plant height.—33 cm.

Plant height (inflorescence included).—34 cm.

Plant width.—73 cm.

Roots.—Fibrous and fleshy; medium thickness; white.

Time to initiate roots.—7-10 days.

Time to produce a rooted plant.—4 weeks.

Foliage:

Type.—Opposite.

Immature, leaf color, upper surface.—Closest to RHS 137C.

Lower surface.—Closest to RHS 138A.

Mature, leaf color, upper surface.—RHS 139A.

Lower surface.—Closest to RHS 137B.

Length.—5.0-5.5 cm.

Width.—2.5-3.5 cm.

Shape.—Ovate.

Base shape.—Rounded to obtuse.

Apex shape.—Acute.

Margin.—Dentate.

Texture, upper.—Hairy.

Texture, lower surface.—Hairy.

Pattern of veining.—Pinnate.

Petioles color.—RHS 139C.

Petioles length.—1.0-1.4 cm.

Diameter of petiole.—0.20 cm.

Petiole strength.—Strong.

Texture (upper and lower surface).—Very short hairs.

Stem:

Color of stem.—RHS 146C.

Length of stem.—14-22 cm.

Diameter.—0.3-0.4 cm.

Stem strength.—Strong.

Length internodes.—3.0-4.0 cm.

Texture.—Some hairs.

Inflorescence:

Type.—Umbel like, flattened semi-sphere the florets are sessile on an ovate receptacle.

Blooming habit.—Flowers continuously from spring through fall.

Number of open flowers per inflorescence.—About 26-30.

Quantity of inflorescences per plant.—About 16-25.

Lastingness of individual blooms on the plant.—About 3 weeks (depending on temperatures).

Fragrance.—Slightly spicy.

Umbel horizontal diameter.—3.8-4.2 cm.

Umbel vertical height.—2.5 cm.

Pedicel length.—3.7-7.2 cm.

Pedicel diameter.—1.5-2.0 cm.

Pedicel color.—RHS 146C.

Texture of pedicel.—Pubescent.

5

Strength of pedicel.—Strong.

Peduncle color.—RHS 146C.

Length of peduncle.—3.5-6 cm.

Peduncle diameter.—0.15 cm.

Texture.—Small hairs.

Flower:

Floret form.—Corolla salver-shaped to shallow cup-shaped, with a relatively long tube at the base; each flower subtended by a single bract.

Length of floret.—1.3 cm.

Width of floret.—1.1 cm.

Depth of floret.—1.7 cm.

Young floret, color upper surface.—RHS 13A in center, overlain with RHS 32A on edge.

Young floret, color lower surface.—RHS 53C and RHS 48B.

Mature florets, color upper surface.—RHS 70A.

Mature floret, color lower surface.—RHS 64B.

Apex shape.—Rounded.

Degree of lobation.—Moderate.

Margin.—Entire.

Base.—Fused.

Texture, upper surface.—Smooth.

Lower surface.—Smooth.

Tube, color outer surface.—Closest to RHS 64B.

Tube, color inner surface.—Closest to RHS 158C.

Tube, length.—1.2 cm.

Tube, diameter (at opening).—0.15 cm.

Tube, texture outer surface.—Small hairs.

Inner surface.—Hairs.

Bud (just before opening):

Color.—RHS 46A.

Length.—1.1 cm.

Width.—0.3 cm at the apex.

Shape.—Tubular with a flared apex.

Bract:

Color.—Closest to RHS 144A.

Length.—0.9-1.2 cm.

Diameter.—0.15-0.2 cm.

Texture, upper surface.—Hairs.

Lower surface.—Hairs.

Calyx:

Number of sepals.—5, fused sepals forming a short tube around the base of the floret.

Color of sepals.—RHS 145B.

Length of sepals.—0.3 cm.

Width of sepals.—0.1-0.15 cm.

Apex shape.—Obtuse.

Apex margins.—Entire.

Texture, outer surface.—Small hairs.

Inner surface.—Smooth.

Reproductive organs:

Gynoecium:

Pistil quantity.—One.

Length.—0.4 cm.

Style color.—RHS 159D.

Style length.—0.3 cm.

Stigma color.—RHS 144C.

Ovary color.—RHS 144B.

Ovary length.—0.1 cm.

Ovary diameter.—0.05 cm.

Androecium:

Stamen quantity.—4.

Color of filaments.—RHS 159D.

Length filaments.—0.05-0.1 cm.

Anther color.—RHS 165A.
Length of anthers.—0.1 cm.
Color of pollen.—RHS 10D.
Pollen amount.—Normal.
Hardiness:
USDA zone.—Zone 10a.
Temperature range.—Hardy to 32 degrees F. (0 degrees C.).
Fertility/seed set.—Good.
Seed:
Color.—RHS 177A and RHS 177B.
Length.—0.5-0.7 cm.
Width.—0.3-0.45 cm.

6

Fruit.—Round drupe.
Immature fruit color.—RHS 146B.
Mature fruit color.—RHS 202A.
Mature fruit size.—6-8 cm in diameter.
Texture of mature fruit.—Fleshy.
Disease/pest resistance.—Has not been determined to date.
What is claimed is:
1. A new and distinct variety of *Lantana* plant named 'LANZ0021' substantially as illustrated and described herein.
